UNITED STATES PATENT OFFICE

EDWARD J. WINSLOW, OF CHICAGO, ILLINOIS

REPAIR DEVICE FOR CLOSING RUPTURES IN CONCRETE STRUCTURES

Application filed July 3, 1931. Serial No. 548,570.

This invention relates to devices and methods for repairing or closing and sealing apertures or ruptures in concrete structures or masonry.

5 The principal object of the invention is to provide an improved device for mending or closing and sealing apertures, joints or ruptures in concrete structures or masonry with facility and in such a manner as to permit expansion and contraction of the connected or repaired parts of such structures.

10 Other and further objects of the invention will appear from the following description and claims and from an inspection of the accompanying drawing which is made a part hereof.

15 The invention consists of the features, combinations, details of construction and arrangement and mode of operation of parts and in the improved method of repairing and closing leaks or apertures in concrete structures or masonry, as herein described and claimed.

20 In the accompanying drawing—

25 Figure 1 is a view in elevation of a concrete or masonry wall or structure having an aperture or rupture therein and provided with my improved device for repairing or closing and sealing the same; and

30 Fig. 2 is a view in horizontal section taken on line 2—2 of Fig. 1, looking in the direction indicated by the arrows.

35 In constructing an improved device or closure for repairing or closing and sealing apertures or joints, or ruptures in concrete or masonry structures, such, for example, as a concrete or masonry wall or floor 1, having a leak, aperture, rupture or joint 2 therein to be repaired or closed and sealed in accordance with my improved method and invention, I provide a metallic sheet or strip of sheet metal 3 of suitable dimensions and weight or thickness to withstand the stresses and strains to which the same is subjected in use, such, for example, as a sheet or strip of sheet lead of sufficient length to entirely cover and enclose the aperture or joint to be repaired or closed and of sufficient width to enable said metallic sheet or strip to be firmly secured to the concrete or masonry struc-

ture upon opposite sides of the aperture so as to form a strong waterproof connection between said metallic sheet member or strip and the structure upon which my improved device and invention is to be employed. The metallic sheet member formed of sheet lead has substantially the same coefficient of expansion and contraction as the concrete or masonry of which the structure is formed.

45 The metallic strip or sheet 3 is provided with a series of apertures 4 therein which are spaced apart along the opposite longitudinal margins of said metallic sheet for receiving anchor bolts 5. A plurality of rows of said anchor bolts 5 corresponding with the recesses or bolt-receiving apertures 4 in the metallic strip or plate are anchored in corresponding rows of bolt-receiving recesses or pockets 6 which are made in the structure on opposite sides of the leak, aperture or joint 2 in said structure. The inner headed end of each of said anchor bolts is anchored in a corresponding recess 6 in said structure and encircled by a retaining ring or sleeve 7. Said sleeves are formed of lead or other suitable ductile or compressible metal and adapted to encircle the bolts and to be tamped tightly in place around the same and within the recesses so as to fill the space surrounding the bolts and firmly secure and hold the latter anchored on said recesses or pockets 6 respectively.

50 In order to provide means for effectively filling, closing and sealing the aperture or joint 2 and the apertures and spaces between the metallic sheet or strip 3 and the structure, said apertures and spaces are by preference filled with a suitable quantity of Portland cement or aquarium cement 8 in a plastic condition and adapted to fill and set and harden in and close and hermetically seal said apertures.

55 A suitable undisturbed area and surface portion 9 of said structure located between the apertures 2 and the opposite longitudinal side margins of the strip or plate serves to afford the desired strength for resisting the stresses and strains to which my improved device and the structure are subjected in use and is covered by the cement which is com-

pressed between the metallic sheet or strip 3 and the said enclosed cement-covered area. The metallic sheet or plate 3 is clamped and firmly held in position to cover the aperture in the structure and to cover and compress the cement by threaded nuts 10 which are mounted on and in threaded engagement with the projecting threaded ends of the anchor-bolts 5 on the outside of the said 5 metallic sheet or strip 3. The plastic cement is thus tightly compressed and held in place between the structure and said metallic strip or sheet, and the latter is securely clamped and held in operative position by said anchor-bolts and nuts.

In the form of my improved device and invention shown in the accompanying drawing, a pair of longitudinal approximately 10 parallel recesses or grooves 11 are made in the structure 1 on opposite sides of the aperture or joint 2 and in approximately parallel relation to each other and to the said aperture or joint to be closed and sealed. Longitudinal marginal ribs 12 are provided which 15 are by preference channel-shaped and rigidly secured to the opposite longitudinal margins of the metallic sheet or strip 3 by means of litharge cement or equivalent soldering or welding material applied to the parts to be 20 united, said connected parts being subjected to the process of "burning" or fusing where- by the said parts are united together while 25 in a heated partially melted condition. Each of said longitudinal marginal ribs 12 is 30 adapted to form an integral longitudinal side 35 flange or marginal rib on said metallic sheet or strip. And said longitudinal marginal ribs 12 are by preference on the inner side of said metallic strip or sheet and adapted to 40 be embedded in the plastic cement contained in said grooves 11 on opposite sides of the aperture or joint 2, when the metallic sheet or strip 3 is in place and the device is in operation.

45 Each of the longitudinal grooves 11 connects a series of said bolt-containing recesses or pockets 6 in the structure 1; and said bolt-retaining recesses are of greater depth than the groove in the bottom of which said recesses or pockets are made, and of which they may be said to form a part.

50 After making the longitudinal grooves 11 and the bolt-receiving recesses or pockets 6, and setting the anchor-bolts 5 in said recesses or pockets, said grooves and recesses and the space between the said grooves on opposite sides of the aperture 2 to be closed,—including the space between the surface of the undisturbed area 9 of the structure 1 and the 55 metallic plate or strip 3,—are filled with and covered by the cement 8 in a plastic condition; and the plate or strip 3 with its longitudinal marginal ribs 12 thereon are placed in position to cover and enclose the aperture 60 65 or joint 2, with the said marginal ribs em-

bedded in the plastic cementitious material contained in the grooves 11 and with the anchor bolts 5 in position in the recesses 6 and grooves 11 and extending through the adjacent perforated ribs 12 and bolt-receiving apertures 4 in the metallic sheet or strip. The threaded nuts 10 are then placed upon the anchor-bolts and tightened in clamping engagement with the outer face of the metallic sheet or strip 3 so as to clamp and securely hold the latter in position and compress and securely hold the cement or plastic cementitious material in position to close and seal all of said apertures and spaces containing 70 said cementitious material.

A transverse end groove 13 is made in the concrete or masonry structure and extends across the adjacent extremity of the aperture 2 to be closed and sealed; and a transverse end rib or bar 14 is provided and welded or otherwise secured in rigid engagement with the inner side of the adjacent end margin of the metallic strip or sheet 3 so as to extend across the adjacent end of the aperture 2 in the structure 1, for enclosing the same and for closing and sealing the space between the adjacent ends of the longitudinal ribs 12 and between the ends of said strip or sheet 3 and the surface of the structure adjacent to the end of the said aperture or joint 2 in said structure.

A similar transverse groove 15 is made in the structure 1 in position to extend across the opposite extremity of the aperture or joint 2 in the structure 1 and the corresponding extremities of the longitudinal grooves 11 and transversely between the corresponding end portions of the ribs 12; and a transverse end rib 16 is welded or otherwise rigidly secured to the adjacent end of the sheet or strip 3 and adapted to be embedded in the concrete or cement in a plastic condition in said groove 15 when the metallic strip or sheet 3 with its attached or integral marginal ribs 12, 14 and 16 are secured in operative position 100 upon the structure.

When the aperture 2 to be repaired or closed and sealed is in an upright wall, said upper transverse rib 16 and said groove 15 for receiving the same are usually not required and may be dispensed with; but when said aperture or joint 2 is to be closed and sealed throughout its entire length and enclosed or covered and sealed at both of the extremities of said aperture or joint, the transverse end ribs 14 and 16 and transverse grooves for receiving the same serve to effectively close and seal the space between the ends of the longitudinal side ribs 12 and across the opposite ends of the aperture or joint 2; and the longitudinal side marginal ribs 12 embedded in the cement contained in the grooves 11, together with the cement which covers the enclosed aperture or joint 2 and the enclosed surface of the structure on 115 120 125 130

opposite sides of said aperture or joint, all serve to effectually close and seal said aperture or joint, and render the structure waterproof and strong.

5 Perforated channel-shaped or U-shaped washers 17, having inwardly extending longitudinal flanges 18 adapted to be pressed into abutting clamping engagement with the outer surface of the metallic sheet or strip 3, 10 are provided and mounted upon the projecting ends of the anchor-bolts 5 between the nuts 10 and said metallic sheet or strip, for compressing the longitudinal margins of the latter inward in waterproof adhesive engagement with the cementitious material 8.

These flanged or channel-shaped washers are required and well adapted for use in connection with my improved device, more particularly when, for any reason the longitudinal marginal ribs or channels 12 are not employed; I prefer, however, to employ said longitudinal marginal ribs or flanges 12 which are rigidly secured to the longitudinal margins of said sheet or strip as above described, or by any ordinary and well-known or suitable connecting means.

I claim:

1. In a device of the class described, the combination with a structure having an aperture therein to be closed, of a metallic sheet member having perforations in its opposite longitudinal margins, headed anchor-bolts anchored in the structure on opposite sides of the aperture to be closed and adapted to extend into said perforations in said metallic sheet member for holding the latter in position upon said structure and over said aperture, cementitious material between said metallic sheet member and the surface portions 40 of said structure located on opposite sides of said aperture and adapted to cover and close said aperture and fill the space between said metallic sheet member and the surface of said structure, and clamping means comprising threaded nuts in threaded engagement with said anchor-bolts and in engagement with said metallic sheet member for clamping and holding the latter in leak-proof contact with said cementitious material and in position to cover and enclose said aperture in said structure.

2. In a device of the class described, the combination with a structure having an aperture therein to be closed, of a metallic sheet member having a series of perforations in the opposite longitudinal margins thereof, a series of anchor-bolts anchored in said structure on opposite sides of the aperture to be closed and adapted to extend into said perforations, longitudinal marginal ribs on opposite longitudinal margins of said metallic sheet member, cementitious material enclosed between said metallic sheet member and the surface of said structure on all sides of said aperture and adapted to fill the space between

said marginal ribs and metallic sheet member and cover the surface of the structure on the opposite sides of said aperture for closing said aperture in the structure, and threaded nuts on the threaded ends of said anchor-bolts and in engagement with said metallic sheet member for clamping and holding the latter and said cementitious material in position to cover and close and hermetically seal said aperture in said structure.

3. In a device of the class described, the combination with a structure having an aperture therein to be closed, of a metallic sheet member having perforations in opposite longitudinal margins thereof, anchor-bolts 70 anchored in said structure on opposite sides of the aperture to be closed, said bolts being adapted to extend into said perforations in said metallic sheet member, said structure being provided with longitudinal grooves 75 therein located on opposite sides of said aperture and in substantially parallel relation to each other, cementitious material in said grooves and adapted to fill and close said aperture and the space between said metallic 80 sheet member and the portions of said structure located on opposite sides of said aperture and between said grooves, longitudinal marginal ribs on the opposite margins of said metallic sheet member and embedded in said 85 cementitious material, and threaded nuts on and in threaded engagement with said anchor-bolts and in engagement with the outer surface of said metallic sheet member for clamping and holding the latter in closely fitting clamping engagement with said cementitious material and in position to effect the closing and sealing of said aperture in said structure.

4. In a device of the class described, the combination with a structure having an aperture therein to be closed, of a metallic sheet member having perforations in its opposite longitudinal margins, headed anchor-bolts 95 anchored in the structure on opposite sides of the aperture to be closed and adapted to extend into said perforations in said metallic sheet member for holding the latter in position upon said structure and over said aperture, cementitious material located between 100 said metallic sheet member and the surface of said structure and adapted to cover and close said aperture in said structure, longitudinally flanged metallic channel members 105 extending lengthwise of said metallic sheet member on the opposite longitudinal margins of the same and provided with perforations for receiving said anchor-bolts, and securing means comprising threaded nuts on and in threaded engagement with the ends of 110 said anchor-bolts on the outside of the perforated margins of said metallic sheet member and adapted to securely hold said sheet member in position upon said structure.

5. In a repair device for closing ruptures 115

in concrete and the like structures, including a metal sheet member adapted to overlie the rupture to be sealed and having a series of perforations adjacent the rupture, clamping bolts extending through said perforations, means for anchoring the bolts in the concrete structure adjacent the rupture, and a sealing member positioned between and adapted to be clamped against the concrete structure and the metallic sheet metal member.

6. A repair device for closing ruptures in concrete and the like structures, including a metallic sheet member adapted to overlie the rupture to be closed and having perforations adjacent its marginal edges; clamping bolts extending through said perforations; means for anchoring the bolts in the concrete structure adjacent the rupture; metal sealing members having apertures through which said bolts extend and adapted to be clamped by said bolts between the concrete structure and the metallic sheet member, said sealing members being adapted to space said metallic sheet member from the face of the concrete structure, and a body of cement in the said space between the concrete structure and the metallic sheet member.

7. A repair device for sealing ruptures in concrete structures including a sheet member of non-ferrous metal disposed over the rupture and extending an appreciable distance from the rupture; spacing members on opposite sides of the rupture positioned between the metal sheet and the concrete structure; clamping bolts extending through said metal sheet and spacing members and into the concrete structure; means for anchoring the clamping bolts in said concrete structure and a body of cement filling the space defined by said metal sheet and the concrete and the metal spacing members.

Signed at Chicago, in the county of Cook and State of Illinois, this 24th day of June, 1931.

EDWARD J. WINSLOW.
